UNITED STATES PATENT OFFICE

150,476

DESIGN FOR A STROLLER OR SIMILAR ARTICLE

Vincent R. Trabucco, Steger, Ill., assignor to Steger Products Mfg. Corp., Steger, Ill., a corporation of Illinois

Application May 22, 1947, Serial No. 139,213

Term of patent 14 years

(Cl. D14—14)

To all whom it may concern:

Be it known that I, Vincent R. Trabucco, a citizen of the United States and a resident of the city of Stegar, in the county of Cook and State of Illinois, have invented a new, original, and ornamental Design for a Stroller or Similar Article, of which the following is a specification, reference being had to the accompanying drawing, forming a part thereof.

On the drawing:

Figure 1 is a top plan view of the stroller or similar article, showing my new design, and

Figures 2, 3 and 4 are respectively rear, side and front elevational views thereof.

I claim:

The ornamental design for a stroller or similar article, as shown.

VINCENT R. TRABUCCO.
